COMBINED BENCH MOUNTED GRINDER GUARD,
LIGHT, EYESHIELD AND TOOL REST

Sidney W. Martin, 1714 77th Court, Elmwood Park, Ill.

Filed Nov. 24, 1961, Ser. No. 67,682

Term of patent 14 years

(Cl. D37—1)

FIG. 1

FIG. 2

FIG. 3

FIG. 4

FIG. 1 is a front perspective view of a combined bench-mounted grinder guard, light, eyeshield and tool rest embodying my new design;

FIG. 2 is a left side view thereof;

FIG. 3 is a right side view thereof; and

FIG. 4 is a rear view thereof.

The broken line showing in all figures is for illustrative purposes only.

I claim:

The ornamental design for the combined bench-mounted grinder guard, light, eyeshield and tool rest, as shown and described.
